E. M. JACKSON.

RAIL JOINT.

APPLICATION FILED APR. 8, 1915.

1,145,770.

Patented July 6, 1915.

UNITED STATES PATENT OFFICE.

EDGAR M. JACKSON, OF FRANKLIN, PENNSYLVANIA, ASSIGNOR OF ONE-HALF TO
LOUVERN A. RICHARDS, OF FRANKLIN, PENNSYLVANIA.

RAIL-JOINT.

1,145,770.

Specification of Letters Patent.

Patented July 6, 1915.

Application filed April 8, 1915. Serial No. 20,616.

To all whom it may concern:

Be it known that I, EDGAR M. JACKSON, a citizen of the United States, residing at Franklin, in the county of Venango and 5 State of Pennsylvania, have invented certain new and useful Improvements in Rail-Joints; and I do hereby declare the following to be a full, clear, and exact description of the invention, such as will enable others 10 skilled in the art to which it appertains to make and use the same.

My invention relates to improvements in joints for rails, and it consists in providing a rigid, strong, durable and efficient rail 15 joint which does not require the use of separate fish plates, bolts, nuts, or other fastening means usually found in joints of the character described.

The improved rail joint, as will be here- 20 inafter described, consists primarily of two parts, the chair or seat member, and a sliding member adapted to provide a second fish plate and to complete the chair. In addition to these I provide an automatic gravity-operated lock which automatically locks 25 the two parts in position, but which may be very readily released when desired.

My invention will be understood by reference to the accompanying drawings, in 30 which the same parts are indicated by the same reference symbols throughout the several views.

Figure 1 is a perspective view showing the complete joint, parts being broken 35 away; Fig. 2 is a detail showing in perspective the seat member or chair, parts being broken away; Fig. 3 is a detail showing in perspective the sliding fish plate member; Fig. 4 is an end view of the device of Fig. 40 1, but on a smaller scale; Fig. 5 shows a section across the joint through the key-hole of Figs. 1 and 3, but showing an end view of the gravity lock in elevation, the section being along the broken line 5—5 of 45 Fig. 1 and looking in the direction of the arrows; and Fig. 6 is a detail showing in perspective the gravity lock detached from the device.

A and A' represent two abutting rails 50 which have their abutting ends either cut across, as shown in the ordinary construction, or interlocking as shown at a and a'. The heads of the rails may be of the usual rounded construction, or may be made with 55 square shoulders as shown in Figs. 1, 4 and

5, and the flanges of the rails should preferably be of the usual construction as shown in the same figures. The chair B consists of the base portion 1 having a flat floor 2 adapted to support the bottom of the rail, 60 with a groove 3 adapted to receive one of the flanges of the rail, and with a vertical rib 4 adapted to fit close against the side of the web of the rail and to engage under the shoulder of the head of the rail. At one 65 side of the floor 2 there is a guide groove 5 for the bottom 6 of the sliding fish plate C, and at the end of this groove 5 there is an abutment 7 adapted to engage the cut-away portion 8 of the sliding fish plate C. 70 This fish plate is provided with a floor 2^a adapted to engage beneath the opposite flange of the rail from the floor 2, and also with a groove 3^a corresponding to the groove 3 of the chair B. It is also provided 75 with a vertical rib 4^a corresponding to the rib 4 of the chair.

One corner of the sliding fish plate is recessed, as at 9, to receive the gravity lock D, and registering with this recess 9 is a 80 longitudinal groove 10 in the chair, see Fig. 2, at the end of which longitudinal groove there is an abutment 11 adapted to ordinarily engage the end 12 of the gravity lock D. This gravity lock is provided with a 85 tapered portion 13 terminating in the engaging end 12, and with a deepened front portion 14 which is rounded, as at 15, as shown most clearly in Fig. 6.

If desired, the chair member B may have 90 laterally-projecting flanges B' which serve to support the chair in the cross tie or road-bed, and also afford convenient handles for transporting and laying same. These flanges also serve to give lateral stiffness 95 and strength to the chair member.

In order to assemble the parts the chair member B is placed under one rail, and the adjacent rail is then brought into position, then the gravity lock is inserted in the position shown in full lines in Fig. 2, then the sliding fish plate C is slid into the position shown in Figs. 1, 4 and 5, pressing the gravity lock to the position shown in dotted lines in Fig. 2 until the tip 17 registers with the 100 slot 9, when the nose 12 will rock down and engage the abutment 11. The sliding fish plate is held against withdrawal in the opposite direction by means of the abutment 7. When it is desired for any reason to re- 110

move the sliding fish plate this can be readily accomplished by pushing down on a rod, wire, or nail inserted in the key-hole 16 which registers with the forward portion 17 of the lock D. By rocking this lock D about its rounded portion 15 the tail 12 may be swung clear of the abutment 11, and the lock swung to the horizontal or disengaging position shown in dotted lines in Fig. 2.

10 It will be noted that the two parts B and C may be made of metal sufficiently strong and durable to withstand any wear to which such joints are intended to be subjected, are not likely to get out of order, 15 and may be readily assembled or dis-assembled. It will also be noted that the lock D is contained in a recess which is effectually screened from dirt, or other foreign matter, but should any water get in the 20 same and freeze it can be readily thawed out by any suitable heating apparatus.

The parts are so simple that there is nothing to get out of order, and the joint may be readily constructed so as to be used with rails of any standard or other desired shape.

It will be obvious that various modifications might be made in the herein described construction, combination and arrangement of parts which could be used without departing from the spirit of my invention.

Having thus described my invention, what I claim and desire to secure by Letters Patent of the United States is:—

35 1. In a rail joint the combination with a chair member provided with a floor adapted to support the bottom of the rail, with a groove adapted to receive one flange of the rail, and with a vertical rib adapted to engage against the web of the rail and support the head thereof, and also provided with a longitudinal groove at one side of said floor, with a recess for a lock, of a sliding fish plate having the bottom portion adapted to slide in said longitudinal groove of the chair member, and also provided with a groove to receive the opposite flange of the rail, and with a vertical rib adapted to engage against the web of the rail and 50 to engage the head thereof, said sliding fish plate being provided with a recess to receive and partly inclose the lock, and a lock having a rounded head portion and a tapered tail portion mounted in said recesses in the 55 chair member and the sliding fish plate, and having its tail adapted to automatically engage a lug in the chair member, and its head adapted to engage a shoulder on the sliding fish plate member, whereby the two 60 are locked against relative longitudinal motion, with means for pressing down said lock and tripping the tail thereof, and thus releasing the same from locking engagement when it is desired to dis-assemble the parts 65 substantially as described.

2. In a rail joint the combination with a chair member provided with a floor adapted to support the bottom of the rail, with a groove adapted to receive one flange of the rail, and also provided with a longitudinal groove at one side of said floor, and with a recess for a lock with an abutment at the end of said recess, of a sliding fish plate having the bottom portion adapted to slide in said longitudinal groove of the chair member, and also provided with a groove to receive the opposite flange of the rail, said sliding fish plate being provided with a recess to receive and partly inclose the lock, and with a key-hole for operating the lock, said lock having a rounded head portion and a tapered tail portion mounted in said recesses in the chair member and the sliding fish plate, and having its tail adapted to automatically engage said abutment in the chair member, and its head adapted to engage a shoulder on the sliding fish plate member, whereby the two are locked against relative longitudinal motion, with means operable through said key-hole for pressing down said lock and tripping the tail thereof, and thus releasing the same from locking engagement when it is desired to dis-assemble the parts, substantially as described. 95

3. In a rail joint the combination with a chair member provided with a floor adapted to support the bottom of the rail, with a groove adapted to receive one flange of the rail, and with a vertical rib adapted to engage against the web of the rail and support the head thereof, and also provided with a longitudinal groove at one side of said floor, and with laterally-projecting horizontal flanges at the level of said floor, 100 of a sliding fish plate having the bottom portion adapted to slide in said longitudinal groove of the chair member, and also provided with a groove to receive the opposite flange of the rail, and with a vertical rib 110 adapted to engage against the web of the rail and to engage the head thereof, and means for holding the two in the locked relation, substantially as described.

4. In a rail joint the combination with a 115
chair member provided with a floor adapted
to support the bottom of the rail, with a
groove adapted to receive one flange of the
rail, and with a vertical rib adapted to en- 120
gage against the web of the rail and sup-
port the head thereof, and also provided
with a longitudinal groove at one side of
said floor, with a recess for a lock, of a slid-
ing fish plate having the bottom portion 125
adapted to slide in said longitudinal groove
of the chair member, and also provided with
a groove to receive the opposite flange of the
rail, and with a vertical rib adapted to en- 130
gage against the web of the rail and to en-
gage the head thereof, and also provided

with laterally-projecting horizontal flanges at the level of said floor, said sliding fish plate being provided with a recess to receive and partly inclose the lock, said lock 5 having a rounded head portion and a tapered tail portion mounted in said recesses in the chair member and the sliding fish plate, and having its tail adapted to automatically engage a lug in the chair member, 10 and its head adapted to engage a shoulder on the sliding fish plate member,

whereby the two are locked against relative longitudinal motion, with means for pressing down said lock and tripping the tail thereof, and thus releasing the same 15 from locking engagement when it is desired to dis-assemble the parts, substantially as described.

In testimony whereof, I affix my signature.

EDGAR M. JACKSON.
